(57) **CLAIM**

The ornamental design for a storage box for screwdriver as shown and described.

DESCRIPTION

FIG. 1 is a front and top perspective view of a storage box for screwdriver, showing my design.

FIG. 2 is a rear and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front and top perspective view of the storage box for screwdriver in another position of use; and, FIG. 10 is an enlarged view of detail **10** in FIG. 1.

The dashed broken lines depict portions of the storage box for screwdriver that form no part of the claimed design. The dot-dash broken lines in FIGS. 1 and 10 depict the boundaries of the enlargements and form no part of the claimed design.
